(57) **CLAIM**

The ornamental design for a control device for an automated warehousing system, as shown and described.

DESCRIPTION

FIG. 1 is a front perspective view of my design for a control device for an automated warehousing system;

FIG. 2 is a rear perspective view thereof;

FIG. 3 is a front view thereof;

FIG. 4 is a rear view thereof;

FIG. 5 is a top plan view thereof;

FIG. 6 is a bottom plan view thereof; and,

FIG. 7 is a right side elevational view thereof, the left side elevational view being a mirror image of FIG. 7.

1 Claim, 6 Drawing Sheets

FIG. 1

FIG. 2***FIG. 3***

FIG. 4

FIG. 5***FIG. 6******FIG. 7***
